[57] **CLAIM**

The ornamental design for a combined container and lid, as shown and described.

DESCRIPTION

FIG. 1 is a top perspective view of a combined container and lid showing my new design;

FIG. 2 is a side elevational view thereof, the opposite side being the same in appearance;

FIG. 3 is an elevational view thereof rotated 90° from FIG. 1, the opposite side being the same in appearance;

FIG. 4 is a top plan view thereof;

FIG. 5 is a bottom plan view thereof; and

FIG. 6 is a view similar to FIG. 1, but showing a modified form of my new design wherein the only difference is in the provision of a circular lid.
